UNITED STATES PATENT OFFICE.

THOMAS ABRAHAM LINCOLN STRANGE, OF THRASHER, MISSISSIPPI.

LOGGING-CART.

No. 891,385.

Specification of Letters Patent.

Patented June 23, 1908.

Application filed February 18, 1908. Serial No. 416,473.

To all whom it may concern:

Be it known that I, THOMAS A. L. STRANGE, a citizen of the United States, residing at Thrasher, in the county of Prentiss and State 5 of Mississippi, have invented a new and useful Logging-Cart, of which the following is a specification.

This invention relates to logging carts and is more particularly designed as an improvement upon the truck described and claimed in Patent No. 801,415, granted to me on Oct. 10, 1905, and upon various other forms of carts of this character designed to partly support and drag logs over the ground. 15 Carts of this character are provided with arches extending upward from the axis of the wheels and the logs are raised by means of various devices so as to be supported at their forward ends within these arches. The 20 entire weight of the forward portion of the log is thus supported by the upper portion of the arch. It has been found in practice, however, that when the cart is pulled forward, the frictional contact of the rear portion of 25 the log with the ground results in the upper portion of the arch being pulled backward, this resulting in a corresponding upward movement of the tongue to which the draft animals are connected. This is very undesirable 30 because of the additional strain upon the draft animals which is produced.

The object of the invention is to provide an attachment for carts of this character whereby the means for lifting and supporting 35 a log within an arch is utilized solely for that purpose and not for the additional purpose of pulling the log, there being separate means employed for dragging the log, said means being so mounted that the pull will be exerted from the axis of the cart so that it will 40 not result in the tilting of the arch and a corresponding movement of the tongue.

With these and other objects in view the invention consists of certain novel features 45 of construction and combinations of parts which will be hereinafter more fully described and pointed out in the claims.

In the accompanying drawings is shown the preferred form of the invention.

50 In said drawings: Figure 1 is a perspective view of a cart embodying the present im-

provements, portions of the lifting and supporting mechanism being illustrated. Fig. 2 is a plan view of the parts shown in Fig. 1, the arch being partly broken away. Fig. 3 55 is an inner elevation of a portion of the arch of the cart. Fig. 4 is a detail view of the tightening means employed in connection with the dragging chain.

Referring to the figures by characters of reference, 1—1 designate the wheels of the cart the same carrying spindles 2 located at the lower ends of a central arch 3 there being forwardly extending beams 4 at the ends of the arch which constitute bounds and are 60 parallel to each other, the forward ends of these beams being connected by a cross beam 5 to which the tongue 6 is suitably attached. Tongs 7 are supported within the arch by means of a flexible hoisting element such as 65 a chain 8 but inasmuch as this hoisting mechanism constitutes no part of the present invention it has not been described or shown in detail. The hoisting and supporting mechanism employed may be the same as 70 that covered by my patent heretofore mentioned or it may be of any other form desired.

As heretofore stated when a cart provided solely with means for supporting a log is 80 drawn forward the resistance produced by the contact of the rear portion of the log with the ground results in a backward pull on the upper portion of the arch, thus causing a corresponding upward movement of the tongue. 85 To eliminate this objectionable feature an attachment has been provided which consists of a chain 10 the ends of which are secured to grooved spools or winding devices 11 mounted upon pivot bolts 12 detachably connected to and extending inwardly from the side portions of the arch 3 at points concentric with the wheels 1. Each of these spools has an operating lever 13 fixedly connected to it and provided with a hook 14 designed 90 to be swung downward and placed into engagement with the adjoining portion of the chain 10 as indicated particularly in Figs. 1 and 3. As shown in Fig. 1 this chain 10 is extended through a pulley 16 to which a supplemental chain 17 is connected. This supplemental chain may be of any desired 100

length and has a hook 18 detachably connected to it and designed to be attached to any one of the links of the chain.

It is believed that the operation of the device will be fully understood from the foregoing description. Before the front end of the log has been raised and secured within the arch chains 10 and 17 are extended over the log and the hook 18 is placed in engagement with said supplemental chain and with the end of the log, after which chain 10 is drawn taut in the manner hereinbefore described. After this dragging attachment has been placed in engagement with the log the log can be raised and secured within the arch in any desired manner.

When the car is drawn forward the chain 10 pulls forward upon the rear end of the log, the line of draft extending from said log end 20 to the spools 11. It will thus be seen that the upper portion of the arch is relieved of all strain due to dragging and the danger of tilting the arch as a result of the dragging operation is fully eliminated and the lifting 25 and holding mechanism is relieved of all backward pull due to the frictional contact of the log with the ground.

It is of course to be understood that cables or other flexible elements may be utilized in 30 lieu of the chain shown and described and various other changes may be made without departing from the spirit or sacrificing the advantages of the invention.

As shown in Fig. 3 a bolt opening 19 may 35 be formed in each side of the arch and above the lower or normal position of the spool 11. The pivot bolt 12 of the spool can therefore be inserted within the opening 19 so as to raise the spool and enable the backward pull 40 exerted by the dragged log to equalize or counterbalance the weight of the hounds and tongue.

Although two spools have been shown within the arch and the chain has been described as having its two ends fastened to them it is to be understood that if preferred only one spool can be employed.

By utilizing the supplemental chain and its pulley connection, lateral swinging of the 50 log relative to the cart is permissible when turning the cart, because the pulley will be free to travel along chain 10 as is obvious.

What is claimed is:

1. A device of the character described 55 comprising an arched axle, supporting wheels therefor, means for supporting one end of a log within the arched axle, and means connected to said axle for exerting a draft upon the rear end of the log from the axis of the axle.

60 2. A device of the character described comprising an arched axle, supports therefor, means for supporting the front portion

of a log within the arched axle, and dragging means extending from the axis of the axle for engaging the rear end of said log.

65

3. A device of the character described comprising an arched axle, supports therefor, hounds extending from the axle, means for securing the forward end of a log within the arched portion of the axle, and flexible 70 means adjustably secured to the arch for engaging the rear end of the log, said means extending toward the log from the axis of the axle.

4. A device of the character described 75 comprising an arched axle, supporting means therefor, means for securing the raised end of a log within the arch of the axle, and means upon the axle for engaging a log to prevent tilting of the axle by the dragging of the log.

80

5. A device of the character described comprising an arched axle, a support therefor, hounds extending from the axle, means for holding the raised end of a log within the arch of the axle, a spool carried by the arch, 85 and flexible dragging means secured upon the spool for engaging the rear end of the log.

85

6. A device of the character described comprising supporting wheels, an arched axle carried thereby, means for securing the 90 front end of a log within the arch of the axle, and dragging means connected to the axle and extending from the sides of the arch at the axis thereof for engaging the rear end of said log.

95

7. A device of the character described comprising supporting wheels, an arched axle carried thereby, means for securing the front end of a log within the arch of the axle, winding means carried by the arch near the axis 100 thereof, and a flexible log engaging device connected to and disposed to be drawn taut by the winding means.

8. A device of the character described comprising supporting wheels, an arched axle 105 carried thereby, means for securing the front end of a log within the arch of the axle, and dragging means connected to the axle and comprising winding means supported by the axle near the axis thereof, a flexible log engaging device secured to said means, and a retaining device carried by said means for engagement with the flexible device to hold said device wound upon said means.

110

9. A device of the character described 115 comprising supporting wheels an arched axle carried thereby, means for securing the front end of a log within the arch of the axle, a spool journaled upon the arch near the axis thereof, a flexible log engaging device fastened to and disposed to be wound upon the spool, a lever carried by the spool, and means upon the lever for engaging the flexible device to hold it wound upon the spool.

120

10. A device of the character described comprising supporting wheels, an arched axle carried thereby, means for securing the front end of a log within the arch of the axle, and dragging means connected to the axle and comprising a flexible element, means for adjustably connecting said element to the arch, a pulley mounted upon said element, a supplemental flexible element extending from
- 5
- said pulley, and a log engaging device carried by the supplemental element.

In testimony that I claim the foregoing as my own, I have hereto affixed my signature in the presence of two witnesses.
